UNITED STATES PATENT OFFICE.

AUGUSTE CLAUDE ADOLPHE BOUCHARD, OF NICE, FRANCE.

DEVICE FOR AUTOMATICALLY CONTROLLING LIGHTING-GAS CONDUITS, ELECTRIC CIRCUITS, AND THE LIKE.

1,240,535.

Specification of Letters Patent. Patented Sept. 18, 1917.

Application filed March 30, 1914. Serial No. 828,364.

To all whom it may concern:

Be it known that I, AUGUSTE CLAUDE ADOLPHE BOUCHARD, a citizen of the French Republic, and resident of Nice, France, have 5 invented a certain new and useful Device for Automatically Controlling Lighting-Gas Conduits, Electric Circuits, and the like, of which the following is a specification.

10 This invention relates to a device for controlling the opening and closing of conduits adapted to convey lighting gas, and more particularly to that class of such devices adapted to be used in connection with some 15 means for lighting the inflammable fluid conveyed through said conduits, and has for its primary object the provision of such a device which shall be adapted to automatically open and close such conduits at 20 a desired time of the day.

A still further object of the invention is the provision of a device of the character described with a valve for opening and closing said conduit, the said valve being 25 operated by means of suitable mechanism controlled by other suitable timing mechanism, which is in turn operated in accordance with a predetermined set relative to the time of day the conduit is to be opened 30 or closed.

With the foregoing and other objects in view, as will hereinafter appear, this invention consists in the peculiar combination and arrangement of various correlated elements of a device for automatically controlling lighting gas conduits, as set forth 35 in the following specification and more particularly brought out in the appended claims.

40 Referring to the accompanying drawings forming a portion of this application and in which the same reference characters indicate the same parts wherever used:

Figure 1 is a vertical section through the 45 device.

Fig. 2 is a front view of the same.

Fig. 3 is a section on line A—A of Fig. 1.

Fig. 4 is a view showing certain details.

The device comprises a casing 1, adapted 50 to house a suitable clock-work 2, carrying a spindle 3, on which is mounted an indicating finger 4, secured thereto by means of a clasp 5, to permit of adjustment of the finger 4 upon the spindle 3. The finger 4 is 55 adapted to move in front of a single dial 6,

provided with twenty-four divisions corresponding with the twenty-four hours of the day. The dial 6 is mounted in the casing 1, and is provided at its periphery with two slots 7 and 8, through which extend two 60 indexes 9 and 10, frictionally mounted upon a sleeve carried by the spindle 3, the indexes 9 and 10 projecting over the divisions of the dial 6, without interfering with the finger 4, in order to permit of the indexes 9 and 10 being shifted between and around the dial 6 within the slots 7 and 8. The index 9 is provided with a shoulder 11, and the index 10 is provided with a shoulder 12, the said shoulders being disposed in different vertical planes. Carried by the spindle and adjacent the shoulders 11 and 12 is a pivot 13, carrying a cam head 14, which is adapted upon rotation of the shaft 3, to alternately strike the shoulders 11 and 12, 75 so that the member 13 alternately oscillates toward the left and the right, carrying with it the two levers 15, which by means of rods 16, extending through a central aperture of a partition 17 of the casing 1, oscillate the disk 18, which engages the lower prongs of a forked member 19, slidably mounted upon a spindle 20. The upper prongs of said fork 19 extend on either face of a gear wheel 21, which carries diametrically opposite pins 22. Wheel 21 is keyed upon a shaft 23, which is parallel with respect to shaft 3, and operated by means of the barrel 24 of the clock work 2, through the medium of a gear 24', engaging the gear 25. A regulating blade wheel 26 serves to govern the motion of wheel 21, through the medium of the gear 26'; a shaft 26'' and a second gear 26''' engaging the wheel 24', as shown in Fig. 1, thus causing the rotation 90 of the wheel 26, which by contact with the air, governs the speed of the wheel 21. Upon the forked member 19 is provided a hooked bar 27, normally projecting into the path of said blade wheel 26, preventing rotation thereof for a purpose to be herein- 95 after explained.

The shaft 23 extends beyond the rear wall of the casing 1, and is provided with a square central member 28, which engages a 100 correspondingly shaped end of a spindle 29. 30 designates a gas inflow chamber of any suitable construction, having an outer wall 30' which carries the outer end of the spindle 29. The spindle 29 is provided with 110

a cam member 31, carrying a member 32, provided with two oppositely disposed valve cones 33, adapted to control the inlet and outlet ducts of the gas chamber 30, designated by the numerals 40 and 41 respectively.

In order to prevent the escape of gas from the chamber 30, through the aperture required for the spindle 29, the spindle 29 is 10 provided with a plurality of circular grooves 39, and a double cam packing 34, mounted in a stuffing box 35, in the inner wall of the chamber 30.

The operation of the device is as follows: 15 Should it be desired to light the burners controlled by the device at six o'clock P. M. and to extinguish the same at five o'clock P. M., the index 9 is shifted by hand on division 18 of the dial, and index 10 on division 5, 20 corresponding with the hours of the twenty-four hours of the day, the finger 4 which corresponds with the position of the member 13 reaches division 18 upon dial 6, the cam 14 meets the shoulder 11 and causes the member 25 13 to swing, carrying with it by means of the levers 15 arms 16, and the disk 18 shifts the double fork 19 laterally along its spindle 20. The member 19 is now thrown out of engagement with the wheel 21 and the pins 30 22. Due to the lateral shifting of the member 19 upon shaft 20 and the subsequent rotation of the arms 19 and 27 under the action of the spring 38, the hooked bar 27 is disengaged from the blade wheel 26, so that the 35 parts 26, 21 and 23, including the means necessary to operate the blade wheel 26 move again under the action of gears 24' and 25, causing the rotation of shaft 23, which in turn causes a rotation of the spindle 29 and 40 the eccentric 31 to cause movement of the frame-work 32, to operate the desired valve cone 33 to open said outlet and light the burners, the said gas outlet duct being fully opened after the shaft 23 has performed half 45 a revolution. When the shaft 23 is rotated through an arc of one hundred and eighty degrees, the second pin 22 of wheel 21 strikes the second upper prong of the double fork 19, which has been previously laterally shifted in the path of said pin. When the said 50 second pin 22 strikes the prong the fork 19 pivots to its shaft 20 and pushes the hooked bar 27 into the path of the blade wheel 26, stopping the rotation thereof and the elements connected therewith, leaving the outlet valve open. When the lighting period 55 has elapsed, the member 13 will strike the shoulder 12, and by means of the cam 14, repeat the operation above described, the 60 hooked bar 27 being disengaged from the blade wheel 26, by means of a spring 38, which normally tends to pull said member out of engagement with the blade wheel, whereupon the shaft 23 is again rotated to 65 shift the valves 33 to close the gas ports and

prevent flow therefrom through the burners, a further rotation of the device being stopped in the manner described for the first or opening operation.

What I claim as new and desire to secure 70 by Letters Patent, is:—

1. A device of the character described comprising a clock-work, a shaft driven thereby, a graduated dial, a finger on said shaft in front of said dial, a sleeve on said shaft, indexes on said sleeve, a shoulder on each of said indexes, a pivoted member carried by said shoulder and adapted to be operated by contact with said shoulders, and means controlled by the operation of said 80 pivoted member adapted to open and close a valve.

2. In a device of the character described, the combination with a casing, of a clock-work within, a shaft driven thereby, a dial, 85 an indicating finger on said shaft adapted to coöperate with said dial, a sleeve on said shaft, a plurality of indexes adjustably mounted to said sleeve, a shoulder on each of said indexes, a pivoted member carried 90 by said shaft and adapted to be alternately operated by each of said shoulders, a spindle, a member slidably mounted on said spindle adapted to be operated by said pivoted member upon contact with one of the 95 shoulders, and means carried by said spindle carried member adapted to control the operation of said clock-work.

3. In a device of the character described, the combination with a clock-work, of a 100 shaft driven thereby, an indicating finger on said shaft adapted to coöperate with the dial, a plurality of indexes adjustably mounted on said shaft by means of a sleeve, a shoulder on each of said indexes, a pivoted member carried by said shaft and adapted to be alternately operated by each of said shoulders, a spindle, a forked member slidably mounted thereon, a second shaft adapted to be operated by said clock-work, 105 a wheel on said shaft, pins carried by said wheel and adapted to alternately strike said forked member, connections between the pivoted member and said forked member whereby movement of the pivoted member will cause movement of said forked member, and means carried by said forked member adapted to control the movement of the 110 clock-work.

4. A device of the character described 115 comprising a casing, a clock-work within said casing, a central shaft driven by said clock-work, an indicating finger carried by said clock-work, and a dial adjacent said finger, a sleeve on said shaft, a plurality of indexes mounted on said shaft and adapted to coöperate with said dial, a shoulder on each of said indexes, a pivoted member carried by said shaft and adapted upon rotation to engage one of said shoulders, a spin- 120

dle, a forked member slidably mounted upon said spindle, connections between said forked member and said pivoted member, a second shaft driven by said clock-work, a 5 wheel on said shaft, a plurality of pins on said wheel adapted to alternately engage said forked member, means carried by said fork adapted to control the operation of said clock-work, and means carried by said 10 second shaft adapted to open and close a supply valve.

5. A device of the character described comprising a casing, a clock-work within said casing, a shaft driven by said clock-work, an indicating finger on said shaft, a dial adjacent said finger, a sleeve on said shaft, a plurality of indexes carried by said sleeve and adapted to coöperate with said dial, a shoulder on each of said indexes, a 15 pivoted member carried by said shaft, a cam head on said pivoted member adapted 20

upon rotation to engage one of said shoulders, a spindle, a double forked member slidably mounted upon said spindle, connections between said pivoted member and said 25 double forked member, a governor for the speed of said clock-work, means carried by said forked member adapted to normally engage said governor to prevent rotation thereof, a valve, means for operating said valve normally held inoperative by said forked member, whereby upon a shifting of said pivoted member by means of contact with the shoulders, said forked member will be shifted to permit rotation of the 30 35 governor and operation of the valve.

In testimony whereof I have hereunto set my hand in presence of two witnesses.

AUGUSTE CLAUDE ADOLPHE BOUCHARD.
